2,597,632

SHUTTLE CLEANER FOR SEWING MACHINES

Eli Goldstein, Brooklyn, N. Y.

Application December 21, 1949, Serial No. 134,329

1 Claim. (Cl. 112—218)

1

This invention relates to a sewing machine, and more particularly to a shuttle-cleaning device for sewing machines.

The object of the invention is to provide a device which will maintain the shuttle of a sewing machine clean, whereby lint or other foreign matter will be prevented from breaking the thread or otherwise interfering with the normal operation of the sewing machine.

Another object of the invention is to provide a device which will maintain a sewing machine shuttle clean at all times, whereby there will be effected a saving in time and money that ordinarily is required for performing this cleaning task.

A further object of the invention is to provide a sewing machine shuttle-cleaning device which is extremely simple and inexpensive to manufacture.

Other objects and advantages will be apparent during the course of the following description.

In the accompanying drawings forming a part of this application, and in which like numerals have been used to designate like parts throughout the same:

Figure 1 is a fragmentary front elevational view of a sewing machine showing the cleaning device of the present invention arranged in engagement with the shuttle;

Figure 2 is a perspective view of the shuttle-cleaning device constructed according to the present invention;

Figure 3 is a sectional view taken on the line 3—3 of Figure 1;

Figure 4 is a sectional view taken on the line 4—4 of Figure 1;

Figure 5 is a perspective view of one of the locking pins.

Referring in detail to the drawings, the numeral 10 designates the frame of a conventional sewing machine, such as a high-speed sewing machine that is used by shoemakers. The frame 10 is cut away so as to provide a channel, and the channel includes a wide portion 11 that communicates with a narrower portion 12. The narrow portion 12 of the channel defines a pair of spaced parallel side walls 13 and 14. The numeral 15 designates a thread-carrying shuttle which is rotatably connected to the frame 10, the shuttle 15 being arranged in the wide portion 11 of the channel.

The present invention is directed to a cleaning device or wiper element which serves to remove or wipe lint or other foreign matter from the

2

shuttle 15 so as to prevent the foreign matter from interfering with the normal operation of the sewing machine. The cleaning device of the present invention is designated generally by the numeral 16 and includes a base 17 which is interposed between the side walls 13 and 14 of the frame 10.

The base 17 of the cleaning device 16 is provided with a longitudinally extending bore 18, and slidably arranged in the bore 18 is a pair of lock pins 19. The lock pins 19 have their inner ends tapered, as at 20, Figures 3 and 5. The base 17 is provided with a threaded opening or aperture 21 which communicates with the bore 18. Arranged in threaded engagement with the opening 21 is a set screw 22, the set screw 22 being arranged in engagement with the tapered ends 20 of the lock pins 19. Thus, by positioning the base 17 between the side walls 13 and 14, and then screwing the set screw 22 into the opening 21, the pair of lock pins 19 will be wedged against the inner surfaces of the side walls 13 and 14 so that the cleaning device will be maintained immobile in its proper position on the frame 10.

Formed integrally with the base 17 or secured thereto is a flange 23. A pin 24 serves to connect a spring member 25 to the flange 23. The spring member 25 includes a first arm 26 that is arranged in engagement with the upper surface of the base 17.

The spring member 25 further includes a second arm 27 which serves to support an oil-carrying pad 28 that may be fabricated of any suitable material, such as felt. Formed integrally with the arm 27 is a clamp bracket 29 which serves to clamp the pad 28 onto the arm 27. The upper portion of the pad 28 is cut away, as at 30, so as to conform in configuration to the arcuate portion of the shuttle 15 which is to be cleaned.

In use, the base 17 of the shuttle-cleaning device 16 is arranged between the side walls 13 and 14 of the sewing machine frame 10. Then, the screw 22 is tightened into the threaded opening 21 so that the lock pins 19 will be forced or wedged against the inner surfaces of the side walls 13 and 14. This will insure that the cleaning device is maintained immobile in its correct position relative to the shuttle 15. The felt pad 28 is saturated with a suitable white oil, and the spring member 25 serves to urge the pad 28 into engagement with the shuttle 15, whereby lint or other foreign material will be wiped from

the thread or shuttle 15, as the shuttle 15 is rotated.

From the foregoing, it is apparent that an automatic shuttle-cleaning device has been provided which will insure that the stitch is maintained free of foreign matter, and whereby the necessity of cleaning the machine will be minimized. Further, the cleaning device of the present invention will eliminate the necessity of using the usual felt padding which is arranged in the upper part of the machine, since the usual felt padding is not satisfactory. The cleaning device of the present invention will insure that the operator does not get splattered with oil, so that shields will not be required to protect the face and eyes from the oil. The shuttle-cleaning device can be used on any type of sewing machine, the shuttle-cleaning device being especially suitable for use on high-speed sewing machines of the type used by shoemakers. The shuttle-cleaning device will maintain the shuttle clean so that broken threads, bad stitches and the like will be prevented, and further, a great deal of time and money will be saved by eliminating the necessity of frequently cleaning the machine.

I claim:

In a sewing machine, the combination with a frame provided with a channel, said channel defining a pair of spaced parallel side walls on opposite sides thereof, and a rotary thread-carrying shuttle positioned in said channel and rotat-

ably supported on said frame, of a cleaning device positioned in said channel, said cleaning device comprising a base interposed between said side walls and provided with a longitudinally extending bore, a pair of lock pins slidably arranged in said bore and arranged in engagement with said side walls, the inner ends of said lock pins being tapered, there being a threaded opening in said base communicating with said bore, a set screw positioned in said opening and arranged in engagement with the tapered ends of said lock pins, a flange projecting upwardly from said base, a spring member including first and second arms, the first arm arranged in engagement with the upper surface of said base and the second arm diverging from one end of said first arm, a pin connecting said spring member at the juncture of said arms with said flange, and an oil-carrying pad supported by said second arm in engagement with said shuttle.

ELI GOLDSTEIN.
